UNITED STATES PATENT OFFICE.

WILLIAM GUTENKUNST AND CHARLES A. GUTENKUNST, OF MILWAUKEE,
WISCONSIN.

TRACK FOR CARRIERS.

SPECIFICATION forming part of Letters Patent No. 426,179, dated April 22, 1890.

Original application filed May 11, 1889, Serial No. 310,417. Divided and this application filed August 14, 1889. Serial No. 320,760. (No model.)

To all whom it may concern:

Be it known that we, WILLIAM GUTENKUNST and CHARLES A. GUTENKUNST, of Milwaukee, in the county of Milwaukee and State 5 of Wisconsin, have invented new and useful Improvements in Tracks for Carriers; and we do hereby declare the following to be a full, clear, and exact description of said invention, reference being had to the accompanying drawings, and to the letters of reference marked thereon, which form a part of this specification.

Our invention relates to the form and construction of a track especially adapted for use 15 with hay-carriers, by which form of track inexpensiveness of construction is had and convenience in putting it up and strength and steadiness of parts are secured.

In the drawings, Figure 1 is a side view of 20 our improved track, showing the devices for supporting it and attachments thereto for the convenience of the carrier. Fig. 2 is a side view of the stop, showing the reverse side to that shown in Fig. 1. Fig. 3 is an under side 25 view of the stop. Fig. 4 is a perspective view of a track-coupling device. Fig. 5 is an under side view of the track with connecting devices, coupling devices, supporting devices, and cross-bars, parts being broken away to 30 show interior portions.

Our carrier-track is formed of two parallel rails A A, preferably constructed of gas-pipe, though a solid rod could be used to advantage in some cases. These pipes are connected 35 together endwise, and are secured rigidly parallel to but at a distance from each other by means of coupling devices having a central cross-bar B and transverse hollow arms C C integral with the cross-bar—one at each end 40 of the bar—in each of which hollow arms the ends of two sections of pipe are inserted, and are secured therein by set-screws D D, turning through the walls of the arms against the pipes, whereby the sections of pipe are secured rigidly in the arms. These coupling and supporting devices are each provided with a hook H, the shank of which passes 45 through the center of the cross-bar in an ap-

erture therefor, and is provided with nuts I, turning on the shank thereof by a screw-thread, one above and the other below the cross-bar, whereby the hook is held rigidly in the cross-bar. 50

Instead of securing the ends of the rails in the hollow arms by means of the set-screws 55 D D, the rails may be made screw-threaded at the ends and turn into the hollow arms, as shown at L in Fig. 5.

It is sometimes convenient to merely connect the ends of the sections of pipe together 60 without a cross-bar, and this we do by using a screw-threaded sleeve M, into which the ends of two sections of pipe are inserted and secured by turning the sleeve thereon.

A stop N, adapted to engage with the mechanism of a carrier and hold it temporarily in a fixed position on the track, is provided with two sets of cross-bars O O, having transverse apertures, which cross-bars are integral with the stop and are provided with set-screws P 65 P, turning through the bars against the rails, whereby the stop is made rigid to the rails. The transverse arms or outer ends of these cross-bars and couplings are preferably made thin in their top part, so that the wheels of 70 the carrier traveling on the track will pass over them with but a slight jar, if any. 75

What we claim as new, and desire to secure by Letters Patent, is—

1. In a carrier-track, the combination, with 80 two round metal rails, of a coupling device having a central cross-bar and transverse hollow arms integral therewith, and means, substantially as described, for securing the ends of the rails in the coupling device. 85

2. In a carrier-track, the combination, with 85 two round metal rails, of a coupling device having a central cross-bar and transverse hollow arms integral therewith, and a hook hanger, the shank of which is secured to the 90 cross-bar centrally, substantially as described.

3. In a carrier-track, the combination, with 95 two round metal rails, of a stop having inclines adapted to resist the lateral thrust of the carrier, and a socket the walls of which are adapted to resist the endwise thrust of

the carrier, which stop is secured to the track
between and below the rails by a cross-bar
having transverse apertures, through which
the rails pass, and means, substantially as
5 described, for securing the stop to the rails
against the thrust of the carrier in the line
of its travel, as set forth.

In testimony whereof we affix our signatures
in presence of two witnesses.

WILLIAM GUTENKUNST.

CHARLES A. GUTENKUNST.
